Primary Examiner — George D Kirschbaum*Assistant Examiner* — Jennifer Watkins(74) *Attorney, Agent, or Firm* — Saidman DesignLaw Group, LLC(57) **CLAIM**

The ornamental design for a toy bucket, as shown and described.

DESCRIPTION

FIG. 1 is a top, front and right side perspective view of a toy bucket showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan side view thereof; and,

FIG. 7 is a bottom plan view thereof.

The broken lines illustrate portions of a toy bucket that form no part of the claim.
